SHAFT CONTROL MECHANISM

Robert T. Cox, Cedar Rapids, Iowa, assignor to
 Collins Radio Company, Cedar Rapids, Iowa, a
 corporation of Iowa

Application July 7, 1951, Serial No. 235,630

7 Claims. (Cl. 200—18)

1

This invention relates in general to shaft positioning mechanisms; and in particular to apparatus wherein it is desired to set up a number of positions and remember the settings.

It is oftentimes desirable to control one or more shafts in a manner such that they may be returned to a pre-set position. For example, in a radio receiver it may be desirable to pre-tune to a plurality of frequencies. For example, a pilot flying across country, will find it desirable to change the frequency of his receiver from various stations to others as he passes from one area to another. Remembering the different frequencies puts an undue strain on the pilot and it is beneficial if he can rotate a dial and automatically select the correct frequency.

It is an object of this invention, therefore, to provide means for setting a control shaft to a plurality of pre-determined positions. Once the positions are set, the operator needs only to turn the main tuning selector dial to the pre-set channel and the set will be tuned automatically.

Another object of this invention is to provide means for setting control switches of a wire saving scheme so that the various positions may be remembered.

Yet another object of this invention is to provide a selector drum with a plurality of channels which control actuating switches for positioning a controlled shaft.

Yet another object of this invention is to provide a coded drum which actuates pawls to set pins on a selector drum.

A feature of this invention is found in the provision for a selector drum with a plurality of rows of pins mounted longitudinally on the selector drum with each pin engageable with a spring that in turn controls the positions of a two-way switch and a pawl. A tuning drum is rotatably mounted adjacent the selector drum and is engageable with the opposite ends of the pawls to position the pins in various combinations so that various combinations of the switches may be obtained.

Another feature of this invention comprises a cam shaft upon which the pawls are supported that may be rotated to disconnect pawls from the pins, thus disconnecting the tuning drum from the selector drum.

Further objects, features and advantages of this invention will become apparent from the following description and claims when read in view of the drawings, in which:

Figure 1 is a top view illustrating the selector drum and the tuning drum of this invention;

2

Figure 2 is a sectional view taken on line 2—2 of Figure 1 with the cam shaft in the down position and tuning drum in the down position;

Figure 3 is a sectional view taken on line 2—2 of Figure 1 with the cam shaft in the down position and the tuning drum in the up position;

Figure 4 is a sectional view taken on line 2—2 of Figure 1 with the cam shaft in the up position and the tuning drum in the down position;

Figure 5 is a sectional view taken on line 2—2 of Figure 1 with the shaft in the up position and the tuning drum in the up position; and

Figure 6 illustrates the control system of this invention.

Referring to Figure 6, a controlled shaft 10 has mounted thereon a toothed stop wheel 11. A pawl 12 is pivotally supported and has an engageable portion 13 for engaging the teeth of the stop wheel 11. Thus, the shaft 10 may be positioned to any of a predetermined number of positions by positioning the pawl between particular teeth of the stop wheel.

A relay 14 controls a pivotally supported armature 16 which is in turn mechanically connected to the pawl 12.

A driving means 17, as for example, an electric motor, has one side connected to one side 18 of a power supply and the other side is connected to a contact 19 which engages the armature 16 when the relay 14 is energized. The armature 16 is connected to ground and therefore, the motor runs when the relay is energized.

The relay is connected to the side 18 of the power supply and to a selector switch, designated generally as 21, which is mounted on the controlled shaft 10. The motor 17 is connected to the controlled shaft 10 through a clutch 20.

The switch 21 is a wafer type switch which is well known to those skilled in the art. For a more detailed description of such a switch, reference may be made to the patent to Richard W. May and Horst M. Schweihofer, No. 2,476,673. The selector switch 21 has a plurality of control wires 22, 23, 24 and 25 connected to it, and each control wire is connected, respectively, to a pivoted contact arm 26, 27, 28 and 29 which forms a part of switches 31, 32, 33 and 34. The switches are single pole-double throw, and the common contacts of each switch are connected together and one set of contacts is connected to ground.

Thus, is provided a system for positioning a shaft 10 to any of a number of positions by setting the contacts 25, 27, 28 and 29 in various combinations of positions. As pointed out in

Patent No. 2,476,673, it will be possible to obtain 2^n-1 positions, where n is the number of control wires of the system.

Thus, with the apparatus of Figure 6 by using four control wires, 15 positions corresponding to the various combinations of the settings of contacts 26, 27, 28 and 29 may be obtained.

This invention discloses apparatus for setting the contacts 26, 27, 28 and 29 to desired positions and remembering these positions so that they may be quickly obtained again.

As best shown in Figure 2, the switches 31, 32, 33 and 34 are mounted to a holding bracket 36 by pins 37. The switches are microswitches with the contacts 26 through 29 extending from the body of the switch so that they may be actuated by moving them a small distance into the switch.

A plurality of springs 38 are connected to the holding bracket and extend past the contacts 26-29. The ends 39 of the spring are arcuately shaped. A pawl 41 for each switch is mounted on a cam shaft 42 which has an enlarged "off-center" portion 43 upon which the pawls 41 may pivot. The cam shaft 42 may be rotated ninety degrees to move the pawls upwardly, but when the cam shaft is in the down position as shown in Figure 2, one end 44 of the pawl engages the arcuate portion 39 of the spring 38 and the opposite end 45 engages the periphery of a set-up disc 47 mounted on a shaft 48.

A selector drum 49 is mounted on a shaft 51 and carries about its periphery a plurality of rows of pins 54. In each row of pins there is a pin for each switch.

With reference to Figure 1, it is seen that the selector drum 49 has a strip 53 which sets over each row of pins and which is supported by holding means 50 and 55 at either end. Slots are formed adjacent holding means 50 and 55 so that strip 53 may be moved longitudinally of the drum. A multiple spring 57 is attached to shaft 51 and biases all of the strips 53 longitudinally of shaft 51.

A plurality of key-hole shaped openings 59 are formed in the strips 53 with an opening for each pin. As best shown in Figure 2, beneath each strip 53 are a plurality of pins 54 which are spring biased outwardly by springs 56.

The pins 54 are formed with a pair of collars 70 and 75 and may be held between strips 53 in either one of two positions. One of the positions is up with the strip 53 received between collars 70 and 75. The other position is with the pin in with the collar 70 engaging the under side of strip 53. The reason for this is that the keyhole shaped openings 59 formed in strips 53 are formed so that their larger portions allow the upper collar 70 to pass therethrough. The collars 75 are slightly larger than collars 70 and cannot pass through the larger portions of the keyhole shaped openings. The small portions of the keyhole shaped openings will not allow either collar to pass therethrough.

Normally, the spring 57 controls the strip 53 so that the pins 54 cannot change position but will be retained in their previously adjusted position.

A lever arm 60 is pivotally supported by bracket 61 and has an engageable portion for moving the strip 53 against the spring 57 so as to allow the pins 54 to move upwardly or downwardly. The opposite end of the lever arm 60 is received in a cam slot 62 cut in a disc 63 mounted on cam shaft 42.

A knob 64 mounted on shaft 42 may be rotated

ninety degrees so that the lever arm 60 will be pivoted by the slot 62, thus moving the strip 53 against spring 57 to allow the pins 54 to be free. The pawls 41 are supported by bearings 65 on the shaft 48 and their opposite end rests against the tuning disc 47.

The apparatus illustrated in Figure 1, comprises two wire saving schemes with each scheme being a four wire system. Reference may be made to Patent No. 2,476,673 for a detailed description of a wire saving scheme. The switches 31, 32, 33 and 34 are the controlling switches for one of the wire saving schemes whereas switches 66, 67, 68 and 69 are the controlling switches 15 for the other wire saving scheme. There are set-up drums 71 and 72 for each wire saving scheme.

The set-up (or tuning) drum 72 is rotatably supported on a shaft 73 which extends through a hollow shaft 48 which supports drum 71. The shaft 73 has a knob 74 attached to it, and shaft 48 has a knob 76 connected to it. The set-up drum 71 carries combination discs 47 which are separated by spacers 77.

The discs 47 on the set-up drum 71 have high and low portions such that all the various combinations possible for switches 31, 32, 33 and 34 may be obtained. In other words, the shaft 48 is rotatably in a detent fashion and in one position, for example, the disc 47 corresponding to switch 34 may be in an up position, the second disc corresponding to switch 33 might be in a down position, a third disc corresponding to switch 32 might be in a down position, and a fourth disc corresponding to switch 31 might be in an up position.

When the cam shaft 42 is in the position shown in Figure 2, the pawls 41 control the positions of pins 54 and actuate the switches 31-34. Thus, as shown when a low part of disc 47 is under the pawl engaging portion 46, the spring 38 is allowed to move upwardly to close switch 34 and pin 54 is allowed to move to the up position.

However, with cam shaft 42 in the down position and a high portion of the disc 47 engaging the pawl 41, the spring 38 will be pushed downwardly forcing the pin 54 within the confines of the selector drum and the switch 34 will not be actuated. This condition is shown in Figure 3.

It is to be remembered that when the cam shaft 42 is in the position shown in Figures 2 and 3, that the strip 53 is pushed against the spring 57 to free the pins 54.

When the cam shaft 42 is cammed to move the pawl 41 upwardly, the pawl loses control of the pins 54 and switches 31-34 for the reason that the end of the pawl 44 does not engage the arcuate portion 39 of spring 38. The strips 53 are locked in their old position when the cam shaft 60 42 is in the position shown in Figures 4 and 5. Figure 4 shows the switch 34 in the unactuated position with the pin 54 in the down position.

Figure 5 shows the switch 34 in the actuated position with the pin 54 in the up position. It is to be noted that the pawl 41 does not control the switch or the pin and it is irrelevant whether the discs 47 are in the up or down position.

The shaft 51 may be rotated by the knob 58 to bring any of the strips 53 under the springs 38 to thus control the set-up of the switches 31-34. Thus, the different strips 53 may be set-up for different shaft positions by rotating the knob 64 until the cam shaft 42 is in the down position corresponding to Figures 2 and 3. Knob 76 may

then be rotated to set the particular combination desired.

The discs 47 through the pawls 41 will then position the pins 54 for the desired combination. The knob 64 may then be rotated to free strips 53, thus allowing them to lock the pins in their position corresponding to the desired setting.

The lever arm 60 has a quick release action due to the shape of the slot 62 so that the pins 54 will be locked by the strip 53 before the pawls 41 are raised so that the pins which are down will remain down after the cam shaft 42 is moved to its up position.

The combination set in the particular strip 53 will be remembered and the next strip may be rotated under the springs 38 by rotating the shaft 51 with the knob 58.

The shaft 48 may be turned to place a new desired combination for the second strip and cam shaft 42 rotated to the down position shown in Figures 2 and 3.

This procedure may be carried out until all of the desired shaft positions are encoded on the selector drum. It is to be understood, of course, that the knob 74 controls the drum 72 for simultaneously setting up the switches 66 through 69.

It is seen that the relation between the two wire saving systems comprising the switches 31 through 34, and 66 through 69, may be arranged so that the end result is that the position of the shaft 51 will control two shaft positions in a desired manner.

Once the set-up operation has been completed, the knob 64 is turned to the position shown in Figure 1 and the set positions are remembered by the selector drum.

Figure 2 illustrates only eight positions for the selector drum, however, any larger number of strips 53 may be placed on the drum.

It is seen that this invention provides means for setting remembered positions on a selector drum such that particular shaft positions may be obtained later when desired.

An example of the operation of the apparatus is an airplane where it is desired to tune a radio receiver, or transmitter to a number of different frequencies prior to take-off.

The selector drum may be tuned to the desired channels by using the various combinations of the discs 47 corresponding to the desired frequency. After the selector drum is set up, the frequency for each position of the selector drum may be noted and a data sheet made for use during flight.

After take-off the flight personnel may tune their communication equipment merely by rotating the knob 58 to the position corresponding to the pre-set frequency. It is to be realized, of course, that the settings may be changed during the flight. However, normally there will be sufficient channels set for the flight.

It is to be realized that when the cam shaft 42 is rotated to the down position, the pins 54 will be changed to the new position corresponding to the position of the shaft 48.

Although this invention has been described with respect to particular embodiments thereof, it is not to be so limited as changes and modifications may be made therein which are within the full intended scope of the invention as defined by the appended claims.

I claim:

1. Apparatus for pre-setting a plurality of control switches so that the settings may be remembered comprising, a selector drum rotatably sup-

ported, a plurality of strips mounted longitudinally of said selector drum and each strip formed with a plurality of key-hole shaped openings, a pin mounted in the selector drum below each key-hole opening, a collar formed on said pins and engageable with said strips, first springs beneath said pins urging them outwardly, a second plurality of springs connected to said strips and urging them longitudinally of the selector drum, a plurality of cantilever springs engageable with said pins, and a plurality of control switches mounted adjacent said cantilever springs and engageable therewith.

2. Apparatus for controlling the setting of a plurality of control switches comprising, a selector drum rotatably supported by a shaft, a knob connected to one end of said shaft, a plurality of strips mounted longitudinally about the periphery of said selector drum and formed with a plurality of key-hole shaped openings, a plurality of pins supported in said selector drum with a pin beneath each key-hole shaped opening, flexible means urging said pins outwardly, a collar formed on said pins of a size large enough to be engaged by the small portion of the key-hole openings but small enough to go through the large portion of the key-hole shaped openings, said strips movable longitudinally of the selector drum, multiple spring means urging said strips to a pin locked position, a plurality of cantilever springs supported adjacent the selector drum with their free ends engageable with one row of said pins, a controlled switch mounted adjacent each of said cantilever springs and engageable therewith so that they may be opened or closed in response to the position of said pins, a cam shaft with an off-center portion rotatably mounted adjacent said selector drum, a plurality of pawls rotatably supported on the off-center portion of said cam shaft and having one end engageable with said pins in the cam down position, a tuning drum rotatably supported adjacent said cam shaft and carrying a plurality of set-up discs thereon, and the other end of said pawls engageable with said set-up discs.

3. Apparatus for pre-setting a plurality of control switches comprising, a holding bracket supporting said control switches, an actuating button extending from each of said control switches, a plurality of cantilever springs attached to said holding bracket and engaging the actuating buttons of said switches, a selector drum rotatably supported, a plurality of longitudinal strips mounted about the periphery of the selector drum with each of said strips formed with a plurality of key-hole shaped openings, multiple spring means engaging said strips, a pin under each key-hole shaped opening, each pin formed with a collar small enough to pass through the large portion of the key-hole shaped opening and large enough to be retained by the small portion of the key-hole shaped opening, a plurality of flexible springs urging each of said pins outwardly from the selector drum, the free ends of said cantilever springs engageable with said pins, a cam shaft with an off-center portion rotatably supported adjacent said selector drum, a plurality of pawls rotatably supported on said cam shaft on the off-center portion, a knob attached to the cam shaft to rotate it 90 degrees from the up position where the pawls are disengaged with the cantilever springs to the down position where the pawls are engaged with the cantilever springs, a tuning drum rotatably supported adjacent said cam shaft and supporting a plurality of set-up

discs, and the opposite ends of said pawls engageable with said set-up discs.

4. Apparatus for controlling the setting of a plurality of control switches with actuating contacts comprising, a holding bracket supporting said plurality of switches, a plurality of cantilever springs attached to said holding bracket with a spring adjacent each of said switches and extending past them to engage their actuating contacts, a selector drum rotatably supported, a plurality of strips mounted about the periphery of said selector drum and movable longitudinally relative thereto, a multiple spring engageable with said strips to spring bias them longitudinally of said selector drum, a plurality of key-hole shaped openings formed in each of said strips, a pin mounted in the selector drum under each key-hole shaped opening, a pair of collars formed on said pins, flexible means urging said pins outwardly from the selector drum, the first of said collars being small enough to pass through the large portion of the key-hole openings but large enough to not pass through the small portion of the key-hole openings, the second collar being too large to pass through the key-hole shaped openings, the free ends of said cantilever springs engageable with said pins, a cam shaft with an off-center portion rotatably supported adjacent said selector drum, a knob connected to said cam shaft to move it from an up to a down position, a plurality of pawls rotatably supported on the off-set portion of said cam shaft, and one end of said pawls engageable with the cantilever springs, a disc mounted on said cam shaft, a cam slot formed in said disc, a lever arm pivotally supported between the cam shaft and the selector drum and with one end engageable in said cam slot and the other end engageable with one of said strips to move it longitudinally of the selector drum against the multiple spring, a tuning drum rotatably supported adjacent the cam shaft, a plurality of set-up discs supported on said tuning drum, and the opposite ends of said pawls engageable with the set-up discs.

5. Apparatus according to claim 4 wherein said tuning drum is formed in two sections with each section rotatable relative to the other and with each section carrying a plurality of set-up discs.

6. Apparatus for controlling a plurality of control switches in different combinations comprising, a holding bracket supporting said control switches, a cantilever spring for each of said switches mounted on said holding bracket, said

springs engageable with the switches to actuate them, a selector drum rotatably supported adjacent the free ends of said cantilever springs, a plurality of strips mounted longitudinally about the said selector drum, said strips movable longitudinally of said selector drum, a multiple spring engageable with the ends of said strips to urge them toward one end of said selector drum, a plurality of key-hole shaped openings formed in said strips, a pin supported in said selector drum beneath each key-hole shaped opening, said pins formed with a pair of collars with the first collar small enough to pass through the larger portion of the key-hole opening but not the smaller portion of the key-hole opening, the second collar too large to pass through the key-hole shaped opening, flexible means urging said pins outwardly from the selector drum, the free ends of said cantilever springs engageable with said pins, a cam shaft with an off-center portion rotatably supported adjacent the selector drum, a plurality of pawls rotatably supported by said cam shaft on the off-set portion, one end of said pawls engageable with the free ends of the cantilever springs, the cam shaft movable from an up to a down position, a disc supported on the cam shaft and formed with a cam slot therein, a lever arm pivotally supported between the selector drum and the cam shaft with one end engageable in the cam slot and the other end engageable with one of said strips, a first tuning drum rotatably supported adjacent the cam shaft, a plurality of set-up discs supported by said tuning drum, a second tuning drum rotatably supported adjacent said cam shaft, a second plurality of set-up discs supported by said second tuning drum, a portion of said pawls having their opposite ends engageable with said first set-up discs, and the remaining pawls having their opposite ends engageable with the second set-up discs.

7. Apparatus according to claim 6 wherein the first and second tuning drums may be rotated relative to each other to independently control two sets of control switches.
